DEODORANT HOLDER OR THE LIKE

Milton Fink, Kewgarden Hills, N. Y.

Application May 25, 1951, Serial No. 15,316

Term of patent 14 years

(Cl. D58—25)

To all whom it may concern:

Be it known that I, Milton Fink, a citizen of the United States, residing at Kewgarden Hills, county of Queens, State of New York, have invented a new, original, and ornamental Design for a Deodorant Holder or the like, of which the following is a specification, reference being had to the accompanying drawing, forming part thereof.

Fig. 1 is a front elevational view of a deodorant holder or the like embodying my new design;

Fig. 2 is a side elevational view of Fig. 1,

Fig. 3 is a top plan view thereof, and

Fig. 4 is a bottom plan view of Fig. 1.

The dominant feature of my design resides in the portions shown in full lines.

I claim:

The ornamental design for a deodorant holder or the like, as shown and described.

MILTON FINK.
